(57) **CLAIM**

The ornamental design for a chest, as shown and described.

DESCRIPTION

FIG. 1 is a left front perspective view of a chest showing my new design;

FIG. 2 is a front elevational view thereof;

FIG. 3 is a side elevational view, the opposite side being a mirror image thereof;

FIG. 4 is a top view thereof; and,

FIG. 5 is a rear elevational view thereof.

The bottom view of the chest is not shown and forms no part of the claimed design.

The fragmented depiction of surface ornamentation shown on the drawer fronts and side panels of the claimed design is understood to exist uniformly across those surfaces.
